TRACK-RAIL LUBRICATING DEVICE

Application filed October 13, 1930. Serial No. 488,311.

My invention relates to devices for lubricating track-rails and the flanges of wheels passing over the same, and is especially useful in preventing undue wear of the rails and 5 reducing noises at curves.

One object of my invention is to provide a lubricant reservoir and mechanism associated therewith for delivering a spray of lubricant adjacent a rail head incident to the 10 passing of wheels therealong, the apparatus being adapted to be carried on and secured to the rail in such manner that no additional support for the apparatus is necessary so that its operation is not affected by the yield 15 of the track.

A further object of the invention is to provide clamping means for yieldingly maintaining the lubricating device under firm pressure against the rail web while permitting its ready removal. My invention thus dispenses with the necessity of piercing the 20 rail and the use of through bolts, and thus it enables the device to be attached to the rail at any point and readily changed from one 25 position to another.

A further object of the invention is to provide a simple and compact rail lubricator designed to fit substantially within the hollow of the rail and to occupy a minimum of 30 space.

Other objects and advantages of the invention will be apparent from the detailed description of one embodiment thereof which follows hereinafter and which has reference 35 to the accompanying drawing.

Of the drawing:

Fig. I represents a front elevation of the lubricating device.

Fig. II represents a cross-sectional view 40 taken as indicated by the arrows II—II of Fig. I.

Fig. III represents an end elevation taken from the opposite end; and

Fig. IV represents a top plan view of a 45 portion of the device.

With particular reference to Fig. I of the drawing, there is illustrated an embodiment of the invention comprising generally a lubricant reservoir 1 in the form of a threaded pipe, a plunger block 2 and a cap block 3,

the blocks snugly fitting the hollow of a rail 4 and being firmly clamped to the rail by means of clamps 5 and 6, respectively.

The cap block 3 serves simply as an end closure for the lubricant reservoir 1. It is 55 internally threaded at 7 to engage one end of the reservoir 1 and is of such shape that it is adapted to rest against the web 8 and flange 9 of the rail. One side of the cap block 3 is provided with a cavity 10 accommodating the clamp 6. In its preferred form the clamp 6 consists of a flat strip of 60 spring steel bent to the shape illustrated and having its ends 11 and 12 turned inward to engage respectively the cavity 10 of the cap 65 block 3 and the flange 9 of the rail 4. The central portion of the clamp 6 is semi-circular in shape, tending to spring the ends 11 and 12 together, and thus the clamp 6 yieldingly but firmly maintains the block 3 against the 70 rail 4.

At the other end the reservoir 1 is threaded at 13 to engage the plunger block 2 which is similar in outline to the cap block 3 previously described, but somewhat larger. The 75 clamp 5 is also generally similar to the cap block clamp 6, except that provision is made for a screw 14 to engage the plunger block 2 and prevent the possibility of its dislodgment.

The plunger block 2 is bored at 15 to accommodate a plunger 16 and spring 17, the plunger head occupying a position near the gauge side of the rail head and directly in the path of the flanges of passing wheels. Beneath the plunger chamber 15 there is an intake passage 18 leading thereto from the reservoir 1 through an intake check valve 19, which projects into the reservoir and includes a valve seat 20, a ball 21, and pin 22, for keeping the ball in place. There is also a discharge passage 23 leading from the bottom of the plunger chamber to an additional passage 24 extending upward through a ball valve 25 to a discharge jet 26. The jet 26 is adapted to deliver a spray of lubricant preferably in a direction towards the throat of the wheel, as illustrated in outline at 27, of the passing vehicle. The ball 29 of the ball valve 25 is confined within certain limits 100

by means of a pin 30. Directly beneath the jet 26 there is a passage 31 communicating with the discharge passage 24 and constituting a by-pass. The by-pass 31 includes a shoulder 32 and ball valve 33 normally 5 pressed against the shoulder 32 by means of a spring 34. The force exerted by the spring 34 is regulated by means of an adjusting screw 35 which fits within a nut 36 on the outside of the plunger block 2. A passage 37 10 leads from the discharge side of the ball valve 33 to the lubricant reservoir 1.

The plunger 16 has a shoulder 38 which normally engages a collar 39 screwed into the top of the plunger block 2. The collar 39 is prevented from turning by means of a tap bolt 40, which engages a recess on the outer surface of the collar 39.

At the top of the reservoir 1 there is provided an opening 41, constituting a filler 20 opening and accommodating a screen 42. The screen 42 is held by means of a collar 43, and the filler opening is closed by a cap 44.

In order to permit the free circulation of 25 oil from the reservoir 1 to the jet 26 by means of the reciprocation of the plunger 16, there is provided a vent 45 in the cap block 3, this vent communicating with the top of the reservoir 1 and preventing the existence of a 30 vacuum in the reservoir.

The operation of the apparatus is as follows:

Upon the passage of a train the flanges of 35 its wheels strike the head of the plunger 16 causing the plunger to be intermittently depressed against the action of the spring 17. The rapid reciprocation of the plunger 16 40 pumps oil from the reservoir 1 through the intake check valve 19 and passage 18 into the plunger chamber 15. From thence the oil is 45 discharged through passages 23 and 24, and the discharge valve 25 to the jet 26, issuing from the jet in the form of a spray against the rail head and passing wheels. A film of oil is thus distributed for some length 50 along the gauge side of the rail head, and this film of oil reduces track wear and the noise of the passing train.

Upon an over accumulation of pressure 55 within the plunger block 2, a portion of the oil will be circulated through the by-pass 31, valve 33, and passage 37 back to the reservoir 1. The resistance offered by the spring 34 and hence the pressure required to operate the ball valve 33 can be regulated by 60 means of the adjusting screw 35.

It will be apparent from the description 65 herein of one practical embodiment of the invention, that the apparatus is so designed as to be substantially accommodated within the hollow of a rail i. e. with its center of gravity between the edge of the rail flange and the rail web and supported entirely thereon. Heretofore track lubricators of the plunger 70 type have projected laterally for some dis-

tance from the rail with a center of gravity beyond the edge of the base of the rail, thus necessitating the use of large through bolts for securing the lubricator to the rail. With my invention the lubricator in its entirety 70 occupies a space which may be no larger than the width of the flange of a standard rail, and by means of the clamping means selected, the lubricator may be readily attached to the rail at any point without the 75 necessity of piercing the rail, and the lubricator may be readily shifted from one point to another.

If by reason of the wearing down of the rail head adjacent the lubricator, or through 80 some other cause, the flanges of passing wheels do not squarely strike the head of the plunger 16, injury to the plunger is prevented because the plunger block 2 is yieldingly maintained against the rail and the block 2 85 will yield upon a force striking the inside edge of the plunger and tending to break the plunger, and thus prevent injury to the apparatus.

While I have described the invention in 90 some detail and with reference to the particular example of it, it will, of course, be apparent that various changes in the form of the apparatus may be made without departing from the spirit of the invention as 95 claimed.

Having thus described my invention, I claim:

1. A track-rail lubricating device comprising a pair of blocks snugly fitting the web 100 of the rail and secured thereto, a lubricant reservoir extending longitudinally of the rail and having its ends retained within said blocks, and means within one of said blocks and operable by a passing wheel for delivering 105 a spray of lubricant.

2. A track-rail lubricating device comprising a lubricant reservoir disposed substantially within the hollow of the rail and extending longitudinally therealong, blocks at 110 the ends of said reservoir, and means for securing the same to the rail web, one of said blocks including a pump operable by a passing wheel for spraying lubricant adjacent the rail head.

3. A track-rail lubricating device comprising a lubricant reservoir, a pump operable by a passing wheel for spraying lubricant adjacent the rail head, said reservoir and pump being disposed substantially within the hollow of the rail on the gauge side thereof, and springs extending beneath the rail and engaging the flange at the other side of the rail, said springs being adapted to clamp the reservoir and pump yieldingly to the rail. 115

4. A track-rail lubricating device comprising a lubricant reservoir, a pair of blocks at the ends of said reservoir, one of said blocks including means operable by a passing wheel 120 for delivering a spray of lubricant, each said 125

block having one side adapted to fit the hollow of the rail and having a cavity in its opposite side, and means engaging said cavities and the rail flange for yieldingly clamping

5 said blocks to the rail.

5. A track-rail lubricating device comprising a lubricant reservoir, a pair of end closures for said reservoir, one of said end closures including means operable by a passing

10 wheel for delivering a spray of lubricant, and spring steel clamps for securing said end closures to the rail with capacity for limited yielding movement.

In testimony whereof, I have hereunto
15 signed my name at Philadelphia, Pennsylvania, this 10 day of October 1930.
